US00D798311S

(12) **United States Design Patent** (10) Patent No.: **US D798,311 S**
Golden et al. (45) Date of Patent: ** *Sep. 26, 2017

(54) **DISPLAY SCREEN WITH GRAPHICAL USER INTERFACE**

- (71) Applicant: **Lennox Industries Inc.**, Richardson, TX (US)
- (72) Inventors: **Kyle Golden**, Plano, TX (US); **Daniel Castillo**, Richardson, TX (US); **Keith Mowery**, Richardson, TX (US); **Jayprakash Charavda**, Irving, TX (US); **Melissa Amoros**, Richardson, TX (US); **Sunil K. Khiani**, Plano, TX (US); **Steve Lazar**, San Antonio, TX (US)
- (73) Assignee: **Lennox Industries Inc.**, Richardson, TX (US)
- (*) Notice: This patent is subject to a terminal disclaimer.
- (**) Term: **15 Years**
- (21) Appl. No.: **29/535,236**
- (22) Filed: **Aug. 5, 2015**

CLAIM

The ornamental design for a display screen with graphical user interface, as shown and described.

DESCRIPTION

FIG. 1 is a front view of a display screen with graphical user interface in accordance with our new design; FIG. 2 is a front view of a second embodiment thereof; FIG. 3 is a front view of a third embodiment thereof; FIG. 4 is a front view of a fourth embodiment thereof; and, FIG. 5 is a front view of a fifth embodiment thereof. The outermost broken line rectangle illustrates a display screen and forms no part of the claimed design.
